UNITED STATES PATENT OFFICE.

ALEXANDER S. RAMAGE, OF DETROIT, MICHIGAN, ASSIGNOR, BY MESNE ASSIGNMENTS, TO BOSTAPH ENGINEERING CORPORATION, OF DETROIT, MICHIGAN, A CORPORATION OF NEW YORK.

METHOD OF TREATING HYDROCARBON OILS.

1,407,770.

Specification of Letters Patent. Patented Feb. 28, 1922.

No Drawing.

Application filed April 6, 1917. Serial No. 160,224.

To all whom it may concern:

Be it known that I, ALEXANDER S. RAMAGE, a subject of the King of Great Britain, residing at Detroit, in the county of Wayne and State of Michigan, have invented certain new and useful Improvements in Methods of Treating Hydrocarbon Oils, of which the following is a specification.

In a copending application Serial No. 160,223, filed herewith, I have described a method of refining hydrocarbon mixtures containing olefines, said method comprising treating the mixture with a relatively small proportion, say one-half to two per cent by weight, of strong sulfuric acid, whereby a tarry precipitate containing hydrolyzable sulfuric acid derivatives of the defines is formed, and then hydrolyzing this precipitate by acting thereon with water, usually in association with an alkaline reagent. The hydrolysis yields bodies of the alcohol type and the subsequent distillation of the neutralized oils yields directly and without material losses a comparatively sweet smelling distillate utilizable as motor spirit and for other purposes.

The present method is a modification of the foregoing, and is more particularly applicable to such fractions or distillates as consist chiefly or largely of olefines or mixtures of olefines with aromatic compounds. Such distillates are obtainable for example in the practice of the process described and claimed in my Patent No. 1,224,787, patented May 1, 1917. The invention is not however limited to these particular mixtures, but is applicable to any hydrocarbon mixture containing olefines whether produced by the cracking or catalytic de-

composition of oils or otherwise. According to the present method, I agitate such mixtures with a relatively large proportion of sulfuric acid, and thereafter hydrolyze the resulting tars. By way of illustration, I may introduce 60-66° Bé. sulfuric acid into the oil, the acid being added slowly, with agitation, and with sufficient cooling to avoid loss of benzol or other volatile hydrocarbons by distillation. This treatment results in the abundant formation of a tarry precipitate which comprises, among other products, hydrolyzable sulfuric acid derivatives of the olefines. As an em-

pirical rule, the amount of acid may be approximately fifty per cent by weight of 55 the olefines in the mixture; that is, a distillate containing fifty per cent of olefines would receive an addition of about twenty-five per cent by weight of 66° Bé. sulfuric acid.

Water is now added with stirring, in quantity sufficient to effect the substantially complete hydrolysis of the tar, as indicated by its disappearance, leaving a mixture of oily and aqueous liquids which stratify when 65 the agitation is stopped. An amount of water representing about ten times the volume of acid employed will usually suffice to accomplish the hydrolysis. Preferably, a suitable neutralizing agent, as lime or 70 soda-ash, is added with the water, since the hydrolytic decomposition of the sulfuric acid derivatives of the olefines is thereby accelerated and rendered more complete.

While the chemical reactions occurring 75 during the process are undoubtedly exceedingly complex, these reactions include the formation of bodies of the alcohol type. For example, amylene existing in the original oil yields, with the sulfuric acid, products 80 which upon hydrolysis form amyl alcohol, which dissolves in the oil, and to a relatively very small extent in the aqueous acid. Reactions of a similar type occur with the other olefines.

The above-described mixture of oil and aqueous acid may be permitted to settle, the acid drawn off, and the oil containing the alcohols and products of polymerization of the olefines may be distilled either in a current of steam or in vacuo, a sufficient amount of alkali, as lime or soda-ash, being added to the oil to neutralize any acid remaining therein. Or, as an alternative, the mixture of oil and aqueous acid may be directly 95 neutralized by a sufficient addition of lime or soda-ash and subjected to distillation in like manner. Preferably, however, as mentioned above, the neutralizing agent is introduced together with the water serving for 100 the hydrolysis.

As a specific example of the practice of the process, a fraction prepared by passing hydrocarbon vapors over iron oxid in the manner disclosed in my Patent No. 1,224,787, 105 above referred to, and boiling entirely be-

tween 70 and 95° C., said fraction containing olefines and aromatics in approximately equal proportions, was treated with twenty-five per cent by weight of 66° Bé. sulfuric acid. A dilute solution of soda-ash was then added to accomplish the hydrolysis of the tar and the neutralization of the product, and the mixture was then carefully fractionated. This fractionation yielded, by 10 volume,—

	Under 78° C.	1.71%
	78-85° C.	9.40%
	85-95° C.	3.16%
15	95-105° C.	1.90%
	105-120° C.	4.27%
	120-150° C.	5.40%
	150-200° C.	4.61%
	200-225° C.	13.42%
20	225-250° C.	21.35%
	250-275° C.	7.70%
	275-300° C.	3.11%
	Over 300° C.	17.10%
	Loss	6.87%
25	Total	100.00

Of the foregoing fractions those up to 150° C. consist largely of aromatics and alcoholic bodies. The fraction from 150° to 30 200° C. is composed chiefly of terpenes and xylol. The fractions above 200° C. comprise unidentified bodies, and the fraction above 275° C. constitutes a lubricating oil of high quality and low freezing-point. 35 The products derived from the olefines by polymerization are not further affected by sulfuric acid, but are nitratable.

It will be observed that the treatment has resulted in a very strong polymerization of 40 the original material, with the result that less than fifteen per cent of the product boils within the temperature limits of the original distillate. It will be observed furthermore that this polymerization has proceeded to 45 such an extent that some 20 per cent of the product is an oil of lubricating grade.

According to the present invention it becomes possible to accomplish a sharp separation between aromatic bodies and olefines 50 of similar boiling-point, a separation which has heretofore presented serious difficulties. The amount of sulfuric acid used is chosen primarily with reference to its action upon the olefines, and is in practice sufficient to 55 act upon all or substantially all of the olefines present, transforming them in part into sulfuric acid derivatives, and in part, presumably by polymerization, into products whose boiling-point is above the range of 60 boiling-points of the aromatic substances. These last-named substances, being unaffected by the sulfuric acid, are directly recoverable by distillation in a state of substantial purity. In recovering aromatics by this 65 method, it is desirable that the sulfuric-acid

tar should be drawn off and separately hydrolyzed and distilled, in order that the aromatics may not be associated with low-boiling alcohols resulting from the hydrolysis.

The statement in certain claims that the 70 sulfuric acid is used in proportion sufficient to transform the olefines of the oil has reference to both types of transformation mentioned above, that is to say, the polymerization and the formation of the corresponding hydrolyzable sulfuric acid derivatives. Where reference is made to effecting hydrolysis of sulfuric acid derivatives by means of water, it is to be understood that the use of water containing dissolved or suspended 80 alkaline reagents is included.

I claim:

1. A method of treating hydrocarbon oils rich in olefines, which consists in reacting thereon with strong sulfuric acid in sufficient 85 proportion to transform the bulk of the olefines into high-boiling bodies, with coincident formation of sulfuric acid derivatives of olefines, and effecting a separation of these products by dissolving and hydrolyzing said 90 sulfuric acid derivatives and distilling off and recovering the volatile products of the hydrolysis.

2. A method of treating hydrocarbon oils rich in olefines, which consists in reacting 95 thereon with strong sulfuric acid in sufficient proportion to transform the bulk of the olefines into high-boiling bodies, with coincident formation of sulfuric acid derivatives of olefines, and effecting a separation of 100 these products by dissolving and hydrolyzing said sulfuric acid derivatives in presence of the oil, and distilling the oil together with the organic products of hydrolysis dissolved therein.

3. A method of treating hydrocarbon oils rich in olefines, which consists in reacting thereon with strong sulfuric acid in the proportion of about fifty per cent by weight of the olefines present, thereby transforming 110 the bulk of the olefines into high-boiling bodies, with coincident formation of sulfuric acid derivatives of the olefines, and effecting a separation of these products by mixing the reaction product with sufficient 115 water to yield therewith a substantially clear solution with coincident hydrolysis, and distilling off and recovering the volatile products of the hydrolysis.

4. A method of treating hydrocarbon oils 120 rich in olefines, which consists in reacting thereon with strong sulfuric acid in the proportion of about fifty per cent by weight of the olefines present, thereby transforming the bulk of the olefines into high-boiling 125 bodies, with coincident formation of sulfuric acid derivatives of the olefines, and effecting a separation of these products by mixing the reaction product, in presence of the oil, with sufficient water to dissolve said precipitate 130

with coincident hydrolysis, and distilling the oil, together with the volatile products of the hydrolysis dissolved therein.

5. A method of treating hydrocarbon mixtures containing olefines and aromatic bodies, which consists in reacting thereon with strong sulfuric acid in proportion sufficient to transform substantially all of the olefines,

10 withdrawing the resulting tarry material, and fractionally separating the aromatic bodies from the high boiling point bodies resulting from the polymerization of the olefines.

In testimony whereof I affix my signature.

ALEXANDER S. RAMAGE.
